UNITED STATES PATENT OFFICE

ADELBERT C. WINTERBERG, OF DREXEL HILL, PENNSYLVANIA, ASSIGNOR TO GENERAL STEEL CASTINGS CORPORATION, OF GRANITE CITY, ILLINOIS, A CORPORATION OF DELAWARE

RAILWAY VEHICLE UNDERFRAME

Application filed October 17, 1931. Serial No. 569,358.

The invention relates to railway rolling stock and consists in an improved construction of underframing for railway vehicles intended primarily to carry water and fuel and the invention is particularly adapted for use in locomotive tender construction.

One object of the invention is to provide a simple and inexpensive underframe casting which in itself may form the bottom of a locomotive tender structure and upon which the sides and ends of the superstructure may be mounted thereby lightening the weight of the tender by eliminating a separate tank bottom.

Another object of the invention is to embody novel features in spaced center sill construction for supporting the vertical longitudinal members of a coal hopper superstructure mounted on and near one end of the underframe.

Another object of the invention is to provide novel features in construction of the underframe and rear end draft gear pocket integral therewith for transmitting the pulling and buffing forces set up in the draft gear pocket to the center sill members of the underframe.

The invention consists in all the novel features hereinafter disclosed and illustrated in the accompanying drawings in which—

Figure 1 is a top view of a locomotive tender underframe embodying the invention.

Figure 2 is a longitudinal vertical section of the underframe taken along the line 2—2 of Figure 1.

Figure 3 is a side view of the underframe.

Figure 4 is a rear end view of the underframe.

Figure 5 is a front end view of the underframe.

Figures 6 to 11 inclusive are detail transverse vertical sections taken along the lines 6—6, 7—7, 8—8, 9—9, 10—10, and 11—11 respectively of Figure 1.

Figure 12 is a fragmentary horizontal section taken along the line 12—12 of Figure 3.

Figure 13 is a fragmentary detail horizontal section taken along the line 13—13 of Figure 2.

The drawings illustrate a locomotive tender one piece underframe casting comprising, as integral parts thereof, side sills 1, end sills 2 and 3, spaced center sills 4, transom members 5, 6, 7, 8, 9, 10, and 11, box shaped bolsters 12 and 13, and draw bar pocket 14 and draft gear pocket 15.

A horizontally disposed web 16 is provided integral with the underframe and extends between the side sills and center sills and transoms and bolsters and end sills and also between the center sills and is substantially imperforate throughout its area to form the bottom of the tender tank.

Suitable openings are provided in the transoms, bolsters, and center sills to permit free passage of water therethrough.

Center sills 4 are of T shaped construction and are provided above the bottom web 16 and extend longitudinally the full length of the underframe between the end sills. These center sills are spaced so that they are located directly below the vertical longitudinal supports 17 for the coal hopper at the front end of the tender.

It is apparent that the improved type of construction permits the use of a simpler and lighter casting than previous constructions having a box shaped center sill extending the full length of the underframe and spaced longitudinal members on each side of the box shaped center sill at the front end for supporting the vertical longitudinal bracing members below the coal hopper.

Draft gear pocket 15, provided below the web 16 and the rear end sill 3, has spaced vertical webs 18 spaced a less distance apart than the spaced center sills 4 located above the web 16. Longitudinal reinforcing members 19 are provided above the web 16 as integral parts of the underframe and in vertical alignment with the vertical webs 18.

Transom member 20 is of substantially box shaped construction and is provided between the spaced center sills 4 and is integral with said center sills and the reinforcing members 19 to transmit the pulling and buffing forces to the center sills 4.

Obviously various features and details herein disclosed may be modified without

causing departure from the spirit of the invention and exclusive use of all features coming within the scope of the claims is contemplated.

5. What is claimed is:

1. In a railway vehicle underframe arranged to serve as a water tight bottom for a tank superstructure applied thereto, a web plate disposed substantially horizontally, 10 centrally disposed longitudinal sill elements extending upwardly from said plate, and a draft gear pocket below said plate, said pocket having vertical walls located intermediate said elements and merging with said web 15 plate.
2. In a railway underframe arranged to form the bottom of a vehicle tank, side sills, end sills, bolsters, a bottom web plate, spaced vertical elements disposed longitudinally of the underframe and between said side sills and extending from end sill to end sill and above said web plate and being interconnected therewith and with said bolsters, and a draft gear pocket below said web plate having vertical walls intermediate said elements, there being continuations of said walls extending upwardly above said web plate.
3. In a railway vehicle underframe arranged to serve as a water tight bottom for a tank superstructure applied thereto, spaced center sills, a bottom web plate disposed substantially horizontally below and extending between said sills, and a draft gear pocket below said web plate, said pocket having vertical walls located intermediate said center sills, and elements extending between said walls and said center sills.
4. In combination, a railway tender underframe including end sills, a tender superstructure mounted on said underframe and including hopper supporting walls, spaced center sills functioning as center sills and provided as integral parts of said underframe and interconnected with and extending 40 between said end sills and adapted at one end to be vertically aligned with and to support said walls.
5. In combination, a tender underframe having center sills, a tender superstructure applied to said underframe and including coal hopper supporting walls, said center sills being so spaced as to be in alignment with said elements and to support the same.
6. In a railway underframe, spaced center 55 sills, a bottom web plate disposed substantially horizontally below and between said sills, a draft gear pocket having spaced side walls depending from said web plate, and longitudinal reinforcing elements in vertical 60 alignment with said side walls and projecting upwardly from said web plate, said reinforcing elements being spaced between said center sills, and members to transmit the pulling and buffing forces in the draft gear 65 pocket to said center sills.

7. In a railway underframe, spaced center sills, a bottom web plate disposed substantially horizontally and below and between said sills, a draft gear pocket having spaced vertical elements projecting downwardly 70 from said web plate, longitudinal reinforcing members vertically aligned with said vertical elements but projecting upwardly from said web plate, said reinforcing members being spaced between said center sills, and a transverse member extending between said center sills and integral with said center sills and reinforcing members to transmit the pulling and buffing forces in the draft gear pocket 75 elements to the center sills.

8. In a railway underframe, end sills, spaced center sills extending between said end sills, a bottom web plate disposed substantially horizontally below and between said sills, a draft gear pocket having spaced side walls depending from said web plate and longitudinal reinforcing elements extending inwardly from one of said end sills and in vertical alignment with said side walls and projecting upwardly from said web plate, 80 said elements being spaced between said center sills, and members transmitting the pulling and buffing forces in the draft gear pocket 85 from said reinforcing elements to said center sills.

9. In a railway underframe casting including as integral parts thereof, end sills, spaced center sills, a bottom web plate disposed substantially horizontally below and extending between said sills, a draft gear pocket having spaced side walls substantially parallel with said center sills and projecting downwardly 90 from said web plate, reinforcing elements parallel with and spaced between said center sills and projecting upwardly from said web plate, said side walls, web plate, and reinforcing elements forming a unit of substantial cross section, and a box shaped transom integral with said center sills and reinforcing elements to transmit the pulling and buffing 95 forces set up in the draft gear pocket to the center sills.

10. In combination, a structure as set forth in claim 8 and a tender superstructure applied to said underframe and including supporting elements for a hopper section of said superstructure, said center sills being vertically aligned with and supporting said hopper supporting elements of said superstructure.

11. In a locomotive tender, an underframe 100 cast in a single piece and comprising side sills, front and rear end sills, spaced longitudinal center sills of substantially T section and extending the full length of the underframe between said end sills, transverse members, certain of which are of box shaped section and serve as bolsters, an imperforate web disposed horizontally below and extending between said sills and transverse members, 105 housings provided with draft gear pockets 110

located adjacent said end sills and below said bottom web, spaced reinforcing elements provided above said bottom web adjacent and near the rear end sill and between said center sills. a box shaped transom integral with said center sills and reinforcing elements, said reinforcing elements and transom serving in combination and association with said rear end housing and center sills to transmit the pulling and buffing forces in said housing to said center sills, a superstructure mounted on said underframe, said underframe serving as a water-tight bottom for said superstructure.

In testimony whereof I hereunto affix my

15 signature this 9th day of October, 1931.

ADELBERT C. WINTEMBERG.
